CLAMP FOR PORTABLE MIXERS

Walter S. Blume, Jr., and Charles H. C. Van Pelt, Jr., Cincinnati, Ohio, assignors to Leyman Manufacturing Corporation, Cincinnati, Ohio, a corporation of Ohio

Application March 20, 1956, Serial No. 572,747

5 Claims. (Cl. 248—16)

The present invention relates to clamping devices and is particularly directed to a clamp for adjustably supporting portable apparatus such as a mixer on the wall of a tank or similar container.

There are many applications in the food processing, chemical, drug, and similar industries in which a portable mixer is used to mix or agitate fluid material within a container. A typical mixer of this type includes a housing enclosing an electric motor which drives an elongated shaft provided with a propeller. The mixer is generally mounted on the top of a side wall of a mixing tank, drum, or the like with the shaft depending into the container so that the propeller is immersed in the fluid to be mixed.

It has been determined that in order to obtain the most efficient mixing, or agitating, the angle of the propeller shaft from perpendicular and the spacing of the propeller from the tank walls must be varied depending upon the physical characteristics of the material being mixed and the nature of the mixing action desired, e. g., blending, stirring, emulsifying, aerating or the like.

The principal object of this invention is to provide clamping means for detachably mounting a mixer on the edge of a tank in any desired position. The present clamp includes means for effecting both horizontal and vertical adjustment of the propeller shaft so that the propeller position and angulation are universally adjustable. The clamp further includes means for securely locking the mixer in any position in which it has been set.

More particularly, a preferred embodiment of the present clamp comprises a tank engaging bracket member such as a generally C-shaped frame threadably carrying a screw which is turned to clamp the tank wall between an arm of the frame and the screw. The frame is also provided with an upwardly extending boss which carries a vertical pin. An externally tapered sleeve provided with a transverse vertical bore fits over the pin and is supported for rotation about a vertical axis by the upper end of the boss. A cylindrical member also including a vertical bore for receiving the pin is mounted within the tapered sleeve.

The mixer housing is provided with two spaced flanges which are mounted on the tapered sleeve. The cylindrical member carries a threaded stud which extends outwardly beyond the sleeve and one of the housing flanges. A thrust bearing plate is fitted over the stud and is adapted for abutment with the adjacent housing flange. A clamping handle threadably engages the end of the stud and is adapted to be threaded inwardly to force the bearing plate against the housing flange.

Horizontal movement of the mixer housing is effected by loosening the clamping handle and rotating the housing, tapered flange and cylindrical member about the vertical pin. Adjustment of the vertical angulation of the mixer housing and the propeller shaft is effected by rotating the housing flanges over the horizontally disposed tapered sleeve. It will readily be appreciated that

this latter adjustment can be combined with the horizontal adjustment previously described to provide universal adjustment of the propeller position.

After the propeller has been properly positioned, the 5 mixer housing is locked in place by threading the locking handle inwardly over the stud carried by the cylindrical plug. This forces the bearing plate against the housing flange and in turn forces the flange inwardly along the tapered sleeve, causing the flange and sleeve to bind there- 10 by preventing further vertical movement of the mixer housing. Threading the clamping handle inwardly also is effective to draw the cylindrical member outwardly to bind it firmly against the vertical pin. Simultaneously, the tapered sleeve is urged inwardly into a similar binding 15 engagement with the vertical pin. The engagement of the cylindrical member and sleeve with this pin functions to prevent movement of the mixer about a vertical axis. In the preferred embodiment, the pin, and the portion of the bore formed in the tapered sleeve, remote 20 from the clamping handle, are knurled to provide a maximum gripping action. Consequently, when the clamping handle is threaded inwardly the mixer is tightly locked in place but when the handle is threaded outwardly the sleeve and cylinder are free to turn about the pin.

25 One of the principal advantages of the present construction is that once the mixer has been locked in place, it is firmly secured in position and does not move even under the influence of severe vibrations or substantial torque. The present clamp has been used with mixers 30 weighing up to 250 pounds rotating as high as 1750 R. P. M. without loosening even after periods of protracted use.

Another advantage of the present invention is that no 35 tools are required to adjust the position of the mixer propeller or to lock the mixer in position after it has been adjusted. To shift the position of the propeller shaft, an operator merely loosens the clamping handle, moves the mixer to the desired position and then tightens the 40 handle to lock the mixer in place. Moreover, the present locking means are extremely rapid, which is highly advantageous for an operator attempting to hold a 250-pound mixer at an angle until it is locked in place.

A still further advantage of the present invention is 45 that the clamp can be economically manufactured. In the first place, the clamp comprises a minimum number of parts; and, secondly, each of the parts is readily cast or machined. This is in sharp contrast to clamps of the type previously proposed including spherical surfaces 50 which are relatively expensive to produce.

An additional advantage of the preferred embodiment 55 of mixer clamp is that it functions to prevent accidental damage to the mixer or tank which might occur during adjustment of the position of the mixer. When previous type mixer clamps are released, the mixer is free to move in any direction and has a tendency to swing rapidly in a downward direction until the agitator shaft strikes the tank walls. In contrast, the present clamp incorporates a degree of taper on the tapered sleeve and flange which 60 is sufficiently small so that these members tend to lock upon themselves when the clamping handle is tightened. Then when the clamping handle is released, the flange and tapered sleeve remain bound with a sufficient force to support mixers up to approximately 150 pounds; and 65 only a very small additional force must be exerted by the operator to support heavier mixers. However the tendency of the tapered sleeve and flange to lock does not affect the release of the unit for movement about the vertical pin. This is highly advantageous since most of 70 the minor adjustments in a tank require motion in a horizontal plane without corresponding adjustments in a vertical plane. With the present clamp, adjustment can be

made in a horizontal plane by merely loosening the locking handle and swiveling the mixer about the vertical pin, without the necessity of supporting its weight to prevent the agitator from swinging downwardly against the tank. In order to free the mixer for downward movement the operator need only loosen the locking handle and tap it inwardly to free the tapered sleeve and flange.

These and other objects and advantages of the present invention will be more readily apparent from a further consideration of the following detailed description of the drawings illustrating a preferred embodiment of the invention.

In the drawings:

Figure 1 is an elevational view of a mixer clamp constructed in accordance with the present invention.

Figure 2 is a cross sectional view of the clamp taken along line 2—2 of Figure 1.

Figure 3 is a cross sectional view taken along line 3—3 of Figure 1.

Figure 4 is a vertical cross sectional view taken through a tank showing the manner in which the mixer is rotated about a horizontal axis.

Figure 5 is a top plan view of the tank and mixer shown in Figure 4, showing the manner in which the mixer is rotated about a vertical axis.

As shown in Figures 1, 4 and 5, a clamp 10 of the present invention is particularly adapted for detachably mounting a portable mixer 11 on top of the side wall 12 of a container 13, such as a mixing tank, drum, or the like. Mixer 11 includes a housing 14, supporting an electric motor and carrying an elongated driven shaft 15 which is adapted to depend into the container. Shaft 15 may be directly driven by the motor or may be driven through a suitable gear drive. It will be understood that the details of the motor and shaft drive constitute no part of the present invention. Shaft 15 carries at its lower end one or more propeller type agitators 16 effective upon rotation to mix the contents of the container.

The details of construction of clamp 10 are best shown in Figures 1-3. As there shown, the clamp comprises a substantially C-shaped frame member 17 which may be forged or cast from steel, bronze or some other suitable material. Frame 17 includes an arm 18 having a flat face adapted for abutting engagement with the inside of container wall 12. A second arm 18 of the clamp is formed with a threaded bearing for carrying a screw 19 which is provided at its inner end with a head 20 for clamping engagement with the outer side of the container wall. The other end of screw 19 carries a suitable operating handle or pin 21 for rotating the screw and firmly clamping frame 17 in place on container wall. Frame 17 is provided with an upstanding boss 22 having a vertical bore 23 formed therein for supporting vertical pin 24, this pin being press-fitted in the bore and being held in place by a wedge shaped cross-pin 25 driven into transverse aperture 26 formed in the boss. The outer end of boss 22 is machined to provide a flat horizontally disposed bearing surface 27.

A sleeve 28 having a vertical cross bore 30 formed therein for loosely receiving pin 24 engages bearing surface 27 of the boss and is supported thereby. Sleeve 28 is provided with a longitudinal, cylindrical inner bore 31, a cylindrical end portion 32, and a tapered portion 33 along which the outer diameter of the sleeve decreases from cylindrical portion 32 to end 34 of the sleeve. Two flat surfaces 35 and 36 are machined on the periphery of the sleeve intermediate the ends thereof. Surface 35 is a bearing surface for engagement with surface 27 of the boss while surface 36 is adapted for cooperative engagement with an enlarged head 37 formed on the upper end of pin 24.

Tapered sleeve 28 directly supports motor housing 11; the housing being provided with two spaced flanges 42 and 43 including bores adapted to receive tapered sleeve

28. More particularly, bore 44 in flange 43 is cylindrical and is of a size only slightly greater than cylindrical end portion 32 of sleeve 28, so that flange 43 is adapted to embrace that portion of the sleeve. Flange 42 is provided with an opening 45 having substantially the same taper as end 33 of sleeve 28, the largest diameter of the bore being smaller than the largest diameter in the sleeve.

As best shown in Figures 2 and 3, flange 42 is of sufficient thickness so that it extends outwardly beyond the end 34 of tapered sleeve 28. This extending portion is preferably machined to form a bearing face 46 adapted for engagement with an annular plate member 47.

An elongated cylindrical member 48 having an outer diameter slightly smaller than longitudinal bore 31 of sleeve 28, is mounted within the sleeve bore. Cylindrical member 48 is provided with a transverse opening 50 for loosely receiving pin 24. Opening 50 of member 48 is preferably provided with knurls 51 on the portion of the opening remote from the tapered portion 33 of sleeve 28, adapted to cooperate with knurls 41 of pin 24, as explained above.

The end of elongated member 48 adjacent to tapered end 33 of sleeve 28 carries a threaded clamping stud 52. This stud may be formed integrally with the cylindrical member or may be secured thereto in any suitable manner, such as by welding or the like. This stud is of sufficient length to extend outwardly beyond the end of sleeve 28 and flange 42 through bearing plate 47. The end of this stud carries a suitable member such as ball crank 53 provided with an internal threaded opening adapted to receive the stud; whereby upon rotation, the member is adapted to be threaded inwardly or outwardly along the stud. Handle 53 also includes a surface 54 disposed for abutting engagement with bearing plate 47.

The mixer clamp is readily assembled by inserting tapered sleeve 28 through the opening in flange 43 and into the tapered opening in flange 42. It will be noted that flange 43 is preferably beveled as at 55 to facilitate this insertion. Next, cylindrical member 48 is inserted in longitudinal bore 31 of tapered sleeve 28. This sleeve is then placed on top of bearing surface 27 of boss 22 and cross bore 30 of the sleeve; opening 50 in cylinder 48, and pin receiving bore 23 in the boss are all brought into alignment. Pin 24 is inserted through the bores in these members and is press-fitted into the boss, after which tapered pin 25 is driven into place to hold the vertical pin in position. Finally, bearing plate 47 is placed over stud 52 and ball crank 53 is threaded over the stud to hold the bearing plate in position.

In use, the mixer is mounted upon a tank by placing frame member 17 on the top of a side wall of the tank and turning handle 21 to rotate screw 19, clamping the side wall of the tank firmly between arm 18 of the frame member and the head 20 carried by the screw.

Next, the position of the propeller shaft is adjusted by turning ball crank 53 to thread that member outwardly over stud 52. This disengages bearing plate 47 from flange 42 and permits flanges 42 and 43 to be shifted slightly toward the small end of sleeve 28. The mixer can then be shifted in a horizontal plane by turning the housing about pivot pin 24; this causes both sleeve 28 and cylindrical member 48 to pivot about the pin; however, flange 42 and sleeve 28 remain in binding engagement so that the mixer does not accidentally pivot downwardly. Vertical adjustment of the mixer is effected by tapping ball crank 53 inwardly to loosen the sleeve and flange, and then rotating the flanges over the sleeve. This provides the adjustment shown in Figure 4. Obviously, both horizontal and vertical adjustments can be combined to bring propeller 14 into any desired position within the tank.

When the mixer has been properly positioned, it is readily clamped and locked into position by rotating ball crank 53 in the opposite direction to thread that member inwardly over stud 52. When ball crank 53 is threaded inwardly, it forces bearing plate 47 against flange

42, forcing this flange inwardly along the tapered portion of sleeve 28. After only very slight movement, flange 42 binds upon the sleeve thereby preventing vertical pivotal movement of the mixer housing. Simultaneously sleeve 28 is urged inwardly into locking engagement with pin 24 (to the left in Figures 2 and 3) and cylindrical member 48 is drawn outwardly (to the right in Figures 2 and 3) so that that member also firmly engages pin 24. Thus, pivotal movement of the mixer housing is prevented by the interlocking engagement of the knurled surface of the cylinder with the knurled periphery of the vertical pin and the engagement of the pin with the tapered sleeve. That is, as best shown in Figure 2, the knurled surface 51 is formed on the side of opening 50 remote from handle 53. This knurled surface engages knurled surface 41 on pin 24 when handle 53 is tightened and cylindrical member 48 is drawn to the right; these knurled surfaces lock tightly against one another to prevent any rotation of the mixer about pin 24. This double-acting lock has proven to be extremely effective in preventing movement of the mixer even after periods of protracted use.

From the above description of the general principles of the present invention and the foregoing disclosure of a preferred embodiment, those skilled in the art will readily comprehend the various modifications to which the present invention is susceptible. For example, while clamp 10 has been described in conjunction with a C-clamp type mounting frame, it will readily be appreciated that boss 22 could be formed on another type of wall engaging clamp, while the remainder of the clamping device could be constructed and would operate in the same manner.

Having described our invention, we claim:

1. A clamp for detachably supporting a portable mixer on the top of a container wall, said clamp comprising a frame member adapted for releasable attachment to a container wall, a vertical pin projecting upwardly from said frame member, a sleeve in engagement with said frame member, said sleeve including a transverse bore receiving said pin and a longitudinal bore, said sleeve having a tapered endwise portion, an elongated member mounted within said longitudinal bore and including a transverse opening receiving said pin, a stud extending outwardly from said member and projecting outwardly beyond the tapered endwise portion of said sleeve, said mixer being provided with a flange in engagement with the tapered portion of said sleeve, and means in threaded engagement with said stud and in abutment with said flange for forcing said flange into binding engagement with said sleeve, whereby said flange is urged into binding engagement with said sleeve and the sleeve and elongated member are urged into binding engagement with the pin.

2. A clamp for supporting a portable mixer on the top of a container wall, said clamp comprising a frame member adapted for releasable attachment to a container wall, a horizontal bearing surface formed on the upper portion of said frame member, a vertical pin projecting upwardly from said bearing surface, a sleeve in engagement with said bearing surface and including a transverse bore receiving said pin and a longitudinal bore, said sleeve having a tapered endwise portion and a cylindrical portion, an elongated member disposed within said longitudinal bore in engagement therewith, and including a cross opening receiving said vertical pin, a stud extending outwardly from an end of said elongated member, said mixer being provided with two spaced flanges in respective engagement with the cylindrical portion and the tapered portion of said sleeve, the flange disposed in engagement with the tapered portion of said sleeve being provided with a tapered opening receiving the sleeve, a bearing plate mounted over said stud and in engagement with said last named flange, and a member threadably engaging said stud and in abutment with said bearing plate, said last named member being adapted to force

said bearing plate against said flange, whereby said flange is urged into binding engagement with said sleeve and the sleeve and elongated member are urged into binding engagement with the pin.

- 5 3. A clamp for supporting a portable mixer on the top of a container wall, said clamp comprising a frame member adapted for releasable attachment to a container wall member, a horizontal bearing surface formed in the upper portion of said frame, a vertical pin projecting upwardly from said bearing surface, a sleeve in engagement with said bearing surface and including a transverse bore receiving said pin and a longitudinal bore, said sleeve having a tapered endwise portion and a cylindrical portion, an elongated member disposed within said longitudinal bore in engagement therewith, and including a cross opening receiving said vertical pin, a stud extending outwardly from an end of said elongated member, said mixer being provided with a flange in engagement with the cylindrical portion and the tapered portion of said sleeve, the flange being provided with a tapered opening receiving the sleeve, a bearing plate mounted over said stud and in engagement with said flange, and a member threadably engaging said stud and in abutment with said bearing plate, said last named member being adapted to force said bearing plate against said flange, whereby said flange is urged into binding engagement with said sleeve and the sleeve and member are urged into binding engagement with the pin.
- 10 4. A clamp for supporting a portable mixer on the top of a container wall, said clamp comprising a frame member adapted for releasable attachment to a container wall member, a horizontal bearing surface formed in the upper portion of said frame member, a vertical pin having a knurled portion on its peripherally projecting upwardly from said bearing surface, a sleeve in engagement with said bearing surface and including a transverse bore receiving said pin and a longitudinal bore, said sleeve including a cylindrical portion and a portion tapering inwardly from said cylindrical portion to an end of said sleeve, an elongated member disposed within said longitudinal bore in engagement therewith, and including a knurled cross opening receiving said vertical pin, a stud extending outwardly from an end of said elongated member, said mixer being provided with two spaced flanges in respective engagement with the cylindrical portion and the tapered portion of said sleeve, the flange disposed in engagement with the tapered portion of said sleeve being provided with a tapering opening receiving the sleeve, and a member threadably engaging said stud and adapted to force said last named flange against said sleeve, whereby said flange is urged into binding engagement with said sleeve and the sleeve and member are urged into binding engagement with the pin.
- 15 5. A clamp for supporting a portable mixer on the top of a container wall, said clamp comprising a frame member adapted for releasable attachment to a container wall, a boss terminating in a horizontal bearing surface formed on the upper portion of said frame member, a vertical pin projecting upwardly from said boss, a sleeve having a flat portion in engagement with said bearing surface and including a transverse bore receiving said pin, said pin having an enlarged head in engagement with the opposite side of said sleeve, said sleeve also including a longitudinal bore, said sleeve having a tapered endwise portion and a cylindrical portion, an elongated cylindrical member disposed within said longitudinal bore in engagement therewith, and including a cross opening receiving said vertical pin, a stud extending outwardly from an end of said elongated member, said mixer being provided with two spaced flanges in respective engagement with the cylindrical portion and the tapered portion of said sleeve, the flange in engagement with the tapered portion of said sleeve being provided with a tapered opening receiving the sleeve, said tapered opening being

- 20 6. A clamp for supporting a portable mixer on the top of a container wall, said clamp comprising a frame member adapted for releasable attachment to a container wall, a boss terminating in a horizontal bearing surface formed on the upper portion of said frame member, a vertical pin projecting upwardly from said boss, a sleeve having a flat portion in engagement with said bearing surface and including a transverse bore receiving said pin, said pin having an enlarged head in engagement with the opposite side of said sleeve, said sleeve also including a longitudinal bore, said sleeve having a tapered endwise portion and a cylindrical portion, an elongated cylindrical member disposed within said longitudinal bore in engagement therewith, and including a cross opening receiving said vertical pin, a stud extending outwardly from an end of said elongated member, said mixer being provided with two spaced flanges in respective engagement with the cylindrical portion and the tapered portion of said sleeve, the flange in engagement with the tapered portion of said sleeve being provided with a tapered opening receiving the sleeve, said tapered opening being substantially the same taper as said sleeve, the largest

diameter of said opening being smaller than the diameter of said sleeve, said last named flange extending outwardly beyond the end of said sleeve, a bearing plate mounted over said stud and in engagement with said last named flange, and a member threadably engaging said stud and in abutment with said bearing plate, said last named member being adapted to force said bearing plate against said flange, whereby said flange is urged to binding en-

gagement with said sleeve and the sleeve and cylindrical member are urged into binding engagement with the pin.
